EDVIN OSSIAN PARCIVAL THEGE, OF STOCKHOLM, SWEDEN, ASSIGNOR TO AKTIE-BOLAGET ATLAS DIESEL, OF STOCKHOLM, SWEDEN.

SLIDE VALVE FOR THE SCAVENGING AIR PUMP AND FOR THE STARTING AIR IN INTERNAL-COMBUSTION ENGINES

Application filed June 21, 1926, Serial No. 117,551, and in Sweden July 7, 1925.

The object of this invention is, in multi-cylinder engines of the two-stroke system, which are started by means of compressed air acting on the scavenging air pumps, to 5 simplify the means which control the passage of the scavenging air to the scavenging air conduit or the so called receiver, common to the different cylinders, and control the starting air. For the said purpose the invention 10 comprises a slide-valve, which is so arranged, that it is able to perform both the said functions. In order to render this possible the slide-valve is shiftable into two different functioning positions. In one of the said 15 positions the said slide-valve controls the passage of the air to the scavenging air pump and from the same and in the other position it controls the passage of the air from the receptacle containing compressed air for the 20 starting of the engine. With the slide-valve a valve device may be combined which controls the passage of the scavenging air from the said receiver to the working cylinders 25 respectively.

Fig. 1 in the accompanying drawings is a vertical section of a two stroke cycle engine; only so much of the engine is shown as is necessary for explaining the invention. Fig. 2 shows in a horizontal section a mechanism 30 for shifting a crank, actuating the slide-valve, through an angle of 180° as the rotary direction of the engine is reversed.

Fig. 3 is a vertical section of the slide-valve mechanism on a larger scale, the section of 35 the lower part being taken along the line 3—3 of Fig. 5;

Fig. 4 is a section on the line 4—4 of Fig. 3; Figs. 5 and 6 are sections on the lines 5—5 and 6—6, respectively, of Fig. 3 and showing 40 the slide-valve in position for controlling the passage of the air to the scavenging air pump and then to the receiver;

Figs. 7 and 8 are sections of the slide-valve on the lines 7—7 and 8—8, respectively, of 45 Fig. 3 and showing the slide-valve in position for controlling the passage of the starting air to and from the working cylinder;

Fig. 9 is a side view partially showing a 50 vertical section of a part of the engine; and Fig. 10 is a detail in side view.

It is presumed that the engine is a multi-cylinder engine provided with a receiver 1 for the scavenging air. 2 is one of the working cylinders with the piston 3, the admission port 4 for the scavenging air and the exhaust port 5 for the gases of combustion. In Fig. 55 9 two of the working cylinders are shown. The part of the cylinder located below the piston 3 is adapted for the compression of the scavenging air and is, for that purpose, provided with a channel 6, constituting the admission passage for the atmospheric air and the discharge passage for the air compressed by the piston 3. 7 is an admission port which 60 through a valve may be connected with a receptacle for the starting air of the engine (said valve and receptacle are not shown in the drawings). 8 is a discharge port for the starting air, which in the engine shown in the drawings communicates with a chamber 70 which is provided round the cylinder 2 and from which the air then passes to the open air through a pipe 6a.

In order now to conduct air for the scavenging of the cylinder to the lower part 75 of the cylinder 2 and from the said part to the receiver, as well as the starting air to the cylinder and from the cylinder to the discharge port for the air, the engine is provided with a slide-valve, which in the form 80 of execution shown in the drawings consists of a cylindrical slide 9, turnable and slidable in the lining 10 of a casing 11. The said slide-valve 9 is moved upwards and downwards by a crank 12, provided on a shaft 12x 85 which is rotated by a shaft 55 through a mechanism, shown in Fig. 2 and described more fully hereinafter. The said shaft 55 is rotated by the main shaft 56 of the engine, Fig. 9, and by means of a spur gearing of the well 90 known construction and enclosed in a casing 57, one of the toothed wheels 58 is shown in Fig. 2. A pitman 13, connected with a head 15x on the spindle 16 of the slide-valve 9 transmits motion from the side crank 12. 95 Spindle 16 is fixed to the head 15x in a rotatable manner and the head 15x slides in a guide 15, while the spindle 16 slides in a tightening sleeve 14. Spindle 16 is fixed to the slide-valve 9 by means of its screw-threaded end 100

and a nut. The central part 17 of the slide-valve 9 is cylindrical or constitutes in any other manner a passage, which extends through the slide-valve and connects the chamber below the slide-valve with the chamber above the slide-valve. The chamber last mentioned communicates directly with the receiver 1. Owing to the described arrangement the slide-valve is balanced, so that the pressure in the receiver 1, does not afford any resistance against the moving of the slide-valve. Slide-valve 9 can be rotated into two different functioning positions by means of an arm 18 to which the spindle 16 is slidably but not rotatably connected for instance by the said arm engaging a square portion 19 of the spindle. The shifting of the arm 18 and thereby the turning of the slide-valve may be effected by any suitable means. The mechanism ought, however, be so arranged, that the slide-valve 9 is turned into the functioning position in which it controls the starting air before the admission valve for the said air is opened.

The slide valve 9 and the lining 10 are provided with a number of co-operating openings. The openings of the slide-valve are divided into two sets, one set located above a transverse partition wall 20, which together with the outer wall, the inner central wall 17 and the end walls 21 of the slide-valve enclose two chambers 22 and 23 in the slide-valve.

The lower chamber 23 is put into communication during each upward stroke of the piston 3 through openings 24 and 25 in the slide-valve with openings 26 and 27 provided in the lining 10 and thus with the channel 6. At the starting position of the arm 18, shown in Figs. 7 and 8, the said chamber 23 communicates through openings 25 in the slide-valve 10 uninterruptedly with openings 38 provided in the lining 10 and leading from the admission port 7. While the arm 18 is in the position shown in Figs. 5 and 6 and corresponding to the running of the engine, the said chamber 23 communicates uninterruptedly through openings 28 in the slide-valve and openings 29 in the lining 10 and openings 30 in the casing 11 with the atmospheric air. During each downward stroke of the piston 3 the upper chamber 22 is put into communication through openings 32 and 33 in the slide-valve 9 with openings 26 and 31 in the lining 10 and thus channel 6. At the starting position of the arm 18 the said chamber 22 communicates uninterruptedly through openings 34 in the slide valve with openings 39 provided in the lining and leading to the discharge port 8, and as the arm 18 is in the position corresponding to the running of the engine, chamber 22 communicates through the openings 34 uninterruptedly with openings 35 provided in the lining 10 and leading to a passage 36 provided in

the casing 11 and communicating through a tube 37 with the receiver 1.

For the starting of the engine the slide-valve is turned into such a position, that the parts of its mantle wall, located between the openings 28 and 34 respectively cover the openings 29 and 35 in the lining 10, and the openings 25 and 34 uncover the openings 38 and 39 respectively. After the valve, controlling the admission port 7 for the compressed air, has been opened, compressed air passes, while the slide-valve 9 is moved upwards, through port 7, openings 38 and 25 into the chamber 23 and from the chamber 23 through the openings 25 and 24 of the slide-valve and the openings 26 and 27 and channel 6 into the cylinder chamber, located below the piston 3, and forces the piston upwards, said piston being at present in its lowermost position. As the piston has arrived at its uppermost position, slide 9 covers the openings 26 and 27, while its openings 32 and 33 uncover the openings 26 and 31, so that air passes from the bottom part of the cylinder 2 through channel 6, openings 26 and 31 in the lining 10 and openings 32 and 33 into the chamber 22 and from the latter through openings 34 and 39, port 8, chamber surrounding the cylinder 2 and pipe 6^a to the atmospheric air. As the piston 3 then arrives at its lowermost position, the communication between the bottom chamber of the cylinder 2 and the port 8 is again interrupted and the said chamber put into communication with the port 7. After the engine has been started the slide-valve 9 is turned by means of the arm 18 into the position shown in Figs. 5 and 6 and corresponding to the running of the engine, in which position the openings 38 ad 39 are covered by the parts of the mantle wall of the slide-valve which are located between the openings 25 and 34 respectively.

If now the crank 12 is rotated in the direction indicated by the arrow in Fig. 1 and consequently the slide-valve is moved upwards, the slide valve puts the chamber 23, which communicates with the atmospheric air through the openings 28, 29 and port 30 into communication with the channel 6 and the lower part of the cylinder 2 through the openings 24 and 25 in the slide-valve 9 and the openings 26 and 27 in the lining 10. In consequence hereof air is sucked into the lower part of the cylinder 2, as the piston 3 moves upwards from its lowermost position, shown in Fig. 1. During the subsequent working stroke of the piston 3 the slide-valve 9 covers the openings 26 and 27, while its openings 32 and 33 uncover the openings 26 and 31. Consequently the air contained by the lower part of the cylinder 2 is forced by the piston 3 through the openings 26 and 31 of the lining and the openings 32 and 33 of the slide-valve and into the chamber 22, from

which the air passes through openings 34 and 35, channel 36 and tube 37 into the receiver 1.

As shown in Figs. 1 and 3 the slide-valve 9 may be coupled to a special slide-valve for controlling the admission of the scavenging air into the working cylinder. In this manner both the slide-valves are moved by the same crank or the like. Figs. 1, 3 and 4 show a slide-valve 40 the spindle 41 of which is connected in a rotatable manner with a disk 42 fixed to the slide-valve 9 by means of screws. The slide-valve 40 is provided with openings 44 cooperating with openings 45 in a lining 46, which is surrounded by a chamber 43*, communicating with a passage 43 leading to the port 4 of the cylinder 2. As the piston 3 during its working stroke uncovers the port 4, the slide-valve 40 still covers the opening 45 and does not uncover the same until the piston has uncovered also the exhaust port 5 and expansion has taken place in the cylinder 2. Compressed air then enters the top part of the cylinder 2 and scavenging is effected. Piston 3 then covers the port 4, and the slide-valve 40 is brought into its closed position. The mantle wall of the slide-valve 40 is fixed to the hub of the slide-valve by means of arms 40* and the openings 44 and 45 have such a length peripherally, that, even if the slide-valve 40 is rotated with the slide-valve 9 the openings 44 and 45 will always constitute an ample passage for the compressed air, as the slide 40 is moved into its upper position.

For the reversing of the rotary direction of the engine, crank 12 is shifted through an angle of 180°. The mechanism for effecting the said shifting is shown in Figs. 2 and 10 and comprises a sleeve 47 which is slidably but not rotatably connected with the shaft 12* of the crank 12 by means of key and slot. The said sleeve 47 has a peripheral groove 48 which is engaged by an arm 49, slideable on a stationary rod 50 which is parallel to the shaft 12*. Arm 49 together with the sleeve 47 may be shifted manually, pneumatically or in any suitable manner by means of a rod 51 fixed to the arm 49. Screw-shaped grooves 52 provided in the sleeve 47 are engaged by pins 53 provided with rollers and fixed to the second sleeve 54. Said sleeve 54 is fixed to a shaft 55, which is rotated by the main shaft in the manner stated above. During its rotation sleeve 54 carries with itself sleeve 47 and shaft 12* owing to engagement of the pins 53 with the grooves 52. As the sleeve 47 is moved from the position shown by full lines to the position shown by dotted lines and vice versa grooves 52 co-operating with the pins 53 impart to the sleeve 47 and thus to the shaft 12* and the crank 12 a rotary motion equal to 180° or the angle necessary for the reversing of the rotary direction of the engine.

I claim:

1. A valve-device for multi-cylinder engines of the two-stroke system, provided with a conduit for scavenging air common to the cylinders and with a pump compressing the said air, said valve device comprising a slide-valve, means for adjusting the slide-valve into two functioning positions, means for operating the slide-valve in each of the said functioning positions, said slide-valve having openings co-operating with openings provided in the lining of the slide-valve casing and communicating with the said pump and conduit, a starting air inlet and a discharge passage respectively, the openings of the slide valve and the lining being so located, that the slide-valve when operated in its one functioning position conducts air to the pump and from the same to the conduit for the scavenging air and when operated in its other functioning position conducts starting air to the piston of the said pump and from the same to the discharge passage for the starting air.

2. A valve device for multi-cylinder engines of the two-stroke system, provided with a conduit for scavenging air common to the cylinders and with a pump compressing the said air, said valve device comprising a cylindrical slide, a transverse partition wall dividing the slide into two chambers, said slide and the lining of the slide valve casing having openings, the openings of the lining communicating with the said pump and conduit, a starting air inlet and a discharge passage respectively, means for rotating the slide into two functioning positions, and means for operating the slide in each of the said functioning positions, the openings of the valve and the lining being so located, that the chambers in one of the functioning positions of the slide-valve control the passage of air to the said pump which is constituted by the chamber below the piston of the engine, and from the pump to the conduit for the scavenging air, and in the other functioning position of the slide-valve controls the passage of starting air to the said pump and from the latter to the discharge passage for the said air.

3. A valve device for multi-cylinder engines of the two-stroke system, provided with a conduit for scavenging air common to the cylinders and with a pump compressing the said air, said valve device comprising a slide-valve, means for adjusting the slide-valve into two functioning positions, means for operating the slide-valve in each of the said functioning positions, said slide-valve having openings co-operating with openings provided in the lining of the slide-valve casing, and communicating with the said pump and conduit, a starting air inlet and a discharge passage respectively, the openings of the slide-valve and the lining being so located,

that the slide-valve when operated in its one functioning position conducts air to the said pump and from the same to the conduit for the scavenging air, and when operated in its other functioning position conducts starting air to the piston of the pump and from the same to the discharge passage for the starting air, and a longitudinal channel provided in the slide-valve and connecting a chamber located in the slide-valve casing at the one end of the slide-valve with a chamber in the said casing located at the other end of the slide-valve and communicating with the conduit of the scavenging air, whereby the slide valve is balanced.

4. A valve device for multi-cylinder engines of the two-stroke system, provided with a conduit for scavenging air common to the cylinders, and with a pump compressing the said air, said valve device comprising a slide-valve, means for adjusting the slide-valve into two functioning positions, means for operating the slide-valve in each of the said functioning positions, said slide-valve having openings co-operating with openings provided in the lining of the slide-valve casing, and communicating with the said pump and conduit, a starting air inlet and a discharge passage respectively, the said openings of the slide-valve and the lining being so located, that the slide valve, when operated in its one functioning position conducts air to the said pump and from the same to the conduit for the scavenging air, and when operated in its other functioning position conducts starting air to the piston of said pump and from the same to the discharge passage for the starting air, a slide controlling the passage of the scavenging air from the said conduit to the working cylinder, and means connecting the said slide with the said slide-valve, whereby the slide and slide-valve are operated by the same means.

5. A valve-device for multi-cylinder engines of the two-stroke system, provided with a conduit for scavenging air common to the cylinders and with a pump compressing the said air, said valve device comprising a slide-valve, means for adjusting the slide-valve into two functioning positions, an eccentric device for operating the slide-valve in each of the said functioning positions, said slide-valve having openings co-operating with openings provided in the lining of the slide-valve casing and communicating with the said pump and conduit, a starting air inlet and a discharge passage respectively, the openings of the slide-valve and the lining being so located, that the slide-valve when operated in its one functioning position conducts air to the said pump and from the same to the conduit for the scavenging air, and when operated in its other functioning position conducts starting air to the piston of the said pump and from the same to the discharge

passage of the starting air, and means for changing the angular position of the said eccentric device for the reversing of the rotary direction of the engine.

In testimony whereof I have hereunto affixed my signature.
